Term of patent 7 years

(Cl. D2—3)

Fig. 4.

Fig. 2.

Fig. 5.

Fig. 3.

FIG. 1 is a front perspective view taken from the top and one side of a combined liquid and cup dispenser showing our new design;

FIG. 2 is a front elevational view thereof;

FIG. 3 is an elevational view taken from the side opposite that shown in FIG. 1;

FIG. 4 is a top plan view thereof; and

FIG. 5 is a rear elevational view thereof.

The dominant features of our design reside in the portions shown in full lines; it being understood that the broken line representation of cups in FIGS. 2 through 5 are for purposes of illustration only.

We claim:

The ornamental design for a combined liquid and cup dispenser, substantially as shown and described.
